UNITED STATES PATENT OFFICE

JOHN U. McDONALD, OF INDIANAPOLIS, INDIANA

PROCESS FOR MAKING PRODUCER GAS

Application filed January 15, 1923. Serial No. 612,750.

This process relates to the manufacture of producer gas for power and heating purposes.

The object of my process is to so arrange 5 the apparatus so that the fuel is in an unbroken column from the source of supply to the producer.

Another object of my process is to supply 10 the producer with air from the top thereof at atmospheric temperature or preheated by hot gases leaving the producer.

A further object is to take away the gases 15 centrally of the producer.

A further object of my invention is to permit 20 the use of oil mixed with other fuel for the purpose of enrichment and thereby make a richer and more valuable and satisfactory gas than is being done in the present producer gas practice.

25 A further object of my process is to cause a total gasification of all combustible constituents of the carbonaceous gas making fuel acted upon in one continuous operation without disturbing the reactions going on in the producer by intermittent feeding of the fuel.

In the accompanying drawings:

Fig. 1 is a side elevation of the gas producer;

30 Fig. 2 is a vertical section through the producer;

Fig. 3 is a horizontal section on line 3—3 of Fig. 2; and

35 Fig. 4 is a horizontal section on line 4—4 of Fig. 2.

The producer consists of a cylindrical shell 1 provided with suitable supporting brackets 2 supported on beams 3, which rest on concrete piers (not shown). The inside of

40 the generator is lined with fire and insulating brick 4, the latter being suitably supported by a circular cast-iron lintel 5 placed at the lower end of the producer. Arranged beneath the producer is a water or ash receptacle 6 provided on the lower side thereof with a circular grooved member 7 adapted to receive rollers 8 supported by the circular U-shaped member 9, which in turn is supported upon a suitable base 10.

50 This rotary ash receptacle is provided at

its lower edge with a gear 11 adapted to mesh with the gear-pinion 12, whereby the ash receptacle may be rotated. The lower end of the producer is received within this pan, the latter being filled with water to effect a 55 seal for the producer.

The ash receptacle 6 is cone-shaped centrally, the central portion 13 thereof projecting upwardly to approximately the same height as the upper edge of the outer portion, 60 and is provided with an opening 14 adapted to receive the gas outlet pipe 15, the upper end of which is provided with a cone-shaped head or cover 16 to prevent dirt and ashes from getting into the open upper end of the gas outlet pipe. The lower end of the outlet pipe 15 is slightly enlarged in diameter as at 17. The numeral 18 indicates a pipe, the upper end of which is enlarged and provided with an annular groove or receptacle 19, 65 which is adapted to receive the lower end 17 of the gas off-take pipe, the said receptacle being filled in order to perfect a water-tight and flexible joint to prevent any strain being placed upon the pipe by the irregular 70 movement of the rotatable ash receptacle.

The lower end of the pipe 18 is received in the seal-pot 20, from which leads the gas outlet pipe 21, the latter leading to a tubular heat-exchanger 22, the upper end of which is 80 in communication with an outlet pipe 23.

Arranged in the top of the producer is a flanged bonnet 24, which is adapted to register with the upper end of the chamber within the producer. Received in the upper end 85 of this bonnet is a feed-pipe 25, the upper end of which is connected to a pipe 26 leading to the feed-hopper 27. The inturned flange of the bonnet 24 which closes the annular space between the end of the feed-pipe 90 25 and the end of the bonnet 24 is provided with a plurality of openings 28, which are adapted to register with openings 29 in the rotatable disk or damper 30, whereby the inlet of cold air may be controlled.

Extending laterally from the bonnet 24 is a hot air inlet pipe 31, leading to the heat-exchanger 22, by which means additional hot air may be injected into the producer, the 95 said exchanger being provided at the lower 100

end thereof with an air-inlet 32. Arranged centrally of the hopper 27 is an oil supply pipe 33, the lower end thereof extending well down into the feed-pipe 26. Immediately below the hopper 27 is a gate 34, by which the fuel being fed to the producer may be controlled. Extending laterally from the bonnet 24 is a steam inlet pipe 35.

In operation, the producer is kept constantly full of fuel, and also a column extending to any desired height above the same. Therefore the feeding of the fuel into the producer is absolutely constant, which means that the reactions taking place within the producer are never disturbed. The fuel is fed into the upper column from the hopper 27, but gradually works down through the producer as the ashes are taken from below.

The air for combustion is taken in at the top of the producer through the hot air inlet pipe 31, or the cold air ports 28, the combustion of fuel commencing at this point. The gases being generated are drawn downwardly through the hot bed of fuel, and also through the ashes at the bottom, constituting a breaking up and purifying of all the combustible constituents of the fuel acted upon. The fuel working downwardly in a constant manner as described, prevents blow-holes from occurring in the fuel-bed, thereby eliminating the necessity of a mechanical stirring device.

The gases are taken off through the gas outlet pipe 15 from the center of the producer, from thence to the seal-pot 20, to the heat exchanger 22, thence through the pipe 23, to a storage tank. If it is desirable, fuel oil may be fed into the generator and mixed with the coal if a richer gas is desired than is now possible to obtain with the present producer gas process.

It will thus be seen that the excess heat available over and above that which is required to maintain the proper temperature for the gasification of a ton of coal, approximately three thousand pounds of oil, can be converted into a fixed and permanent gas. The gas obtained from this amount of oil, combined with the gas from the coal, would amount to approximately two hundred and forty thousand cubic feet of gas of three hundred B. t. u. per cubic foot, which would be very satisfactory for industrial purposes.

It will thus be seen that the fuel is in an unbroken column, that the air is taken in at the top in a very steady and uniform manner, means being provided for taking air in either at atmospheric temperature or preheated by the hot gases leaving the producer. The gases are taken away from the producer centrally thereof near the bottom, consequently the gas is not drawn off to one side of the producer, which naturally narrows the path of exit, or any suitable mechanical means for the work required to properly execute the process.

By drawing the gas down through a bed of

incandescent carbon the tarry constituents of the fuel are broken up into fixed and permanent gases, after which the total combined gases pass through a bed of ashes and are purified to an appreciable degree before leaving the producer through the outlet pipe. 70

I claim:

1. A process for making producer gas including feeding fuel in a continuous unbroken gravity controlled column down through the top of a gas producer, admitting a supply of air to the top of said producer at points circumferentially of said fuel column at the entrance thereof into said producer, withdrawing the liberated gas through a centrally located off-take pipe substantially at the bottom of said producer, and rotating the off-take pipe for agitating the lower portion of the fuel bed in the producer. 75

2. A process for making producer gas including feeding fuel in a continuous unbroken gravity controlled column down through the top of a gas producer, admitting air to the top of said generator at a plurality of points about the periphery of said fuel column and at the point where said fuel column enters said producer; withdrawing the liberated gas through a centrally located off-take pipe substantially at the bottom of said producer, sealing the bottom of said producer by enclosing said bottom in water contained in an ash and water receptacle, supporting the off-take pipe upon said ash and water receptacle, and rotating said receptacle and off-take pipe for agitating the lower portion of the fuel 90 bed in the producer. 95

3. A process for making producer gas in a down draft producer including feeding fuel in a continuous unbroken gravity controlled column down through the top of the gas producer and from the top to the bottom thereof, admitting air to the top of said producer peripherally of the fuel column and at the point where the fuel column enters the producer, withdrawing the liberated gas through a centrally located off-take pipe substantially at the bottom of said producer, agitating the bottom of the fuel bed with said off-take pipe, sealing the bottom of said producer by enclosing said bottom in water contained in an ash and water receptacle, rotating said receptacle and off-take pipe for agitating the lower portion of the fuel bed in the producer, passing the gas from the off-take pipe through a seal pot, and sealing the communication of said off-take pipe with the seal pot. 110

In testimony whereof I affix my signature.
JOHN U. McDONALD.
